GRINDING MACHINE

Eugene F. Haas, Cincinnati, Ohio, assignor to
 Cincinnati Grinders Incorporated, Cincinnati,
 Ohio, a corporation of Ohio

Application February 14, 1931, Serial No. 515,807

13 Claims. (Cl. 51—48)

This invention relates to improvements in grinding machines and especially to improvements in a mechanism for effecting a slight reciprocating movement of a grinding wheel and its spindle.

In the grinding and finishing of the surface of work pieces it has been customary to effect a slight reciprocation of the axes of the work and grinding wheel to break up grinding or grain lines on the said surface of the work. In the past this reciprocation was continuous during the entire grinding operation thereby utilizing the entire surface of the grinding wheel. In some classes of work this is objectionable and the best finish cannot be obtained since the entire face of the wheel will be equally broken down during use. By this invention it is proposed to utilize only a part of the grinding wheel face for the major part of the grinding operation and employ the remainder of the face of said wheel for the finish grinding thereof and for producing the desired finish on the work.

It is, therefore, one of the principal objects of the present invention to provide improved means for effecting the said reciprocation of a grinding wheel and its spindle.

Another object of the invention is the provision of a mechanism that may be readily adjusted for effecting an intermittent reciprocation of a spindle or may be adjusted for effecting a continuous reciprocation of the spindle.

A further object of the invention is the provision of a spindle reciprocating mechanism so arranged as to effect a shifting of the spindle at a predetermined point in the cycle of operation of a machine tool organization.

Other objects and advantages of the present invention should be readily apparent by reference to the following specification considered in conjunction with the accompanying drawings and it is to be understood that any modifications may be made in the exact structural details there shown and described, within the scope of the appended claims, without departing from or exceeding the spirit of the invention.

In the drawings:

Figure 1 is a front elevational view of a grinding machine embodying the principles of this invention.

Figure 2 is a top plan view of the machine shown in Figure 1.

Figure 3 is an end elevational view of the machine as seen from line 3—3 of Figure 1.

Figure 4 is a sectional view taken on line 4—4 of Figure 2.

Figure 5 is a sectional view on line 5—5 of Figure 4.

Figure 6 is a sectional view on line 6—6 of Figure 4.

Figure 7 is a diagrammatic view showing the 5 hydraulic circuit employed.

Throughout the several views of the drawings similar reference characters are employed to denote the same or similar parts.

For the purposes of illustration there has been 10 chosen a centerless grinder with which the improved spindle reciprocating mechanism is employed but it is to be understood that the mechanism may be used in any other organization requiring a shifting of a spindle or a member 15 at a given point in the cycle of operation.

In the drawings the reference character 10 indicates the bed of a grinding machine from which a pedestal 11 rises for rotatably supporting a spindle 12 to the end of which the grinding wheel 13 is secured. Any suitable or desirable means may be employed for rotating the spindle and its supported grinding wheel at a high grinding rate of speed. The bed 10 is further provided on its upper surface with ways 14 for the lower slide 15 in turn provided with ways 16 for a second or upper slide 17. The upper slide 17 is provided with a head 18 rotatably supporting a spindle for the regulating wheel 19 rotatable as a unit in a clockwise direction at a relatively slow work controlling rate of speed. The head 18 is secured to the slide 17 in such a manner that it may be swiveled to dispose the axis of the regulating wheel and its spindle at an angle to the horizontal plane 30 of the axis of the grinding wheel and its spindle so that a suitable feeding thrust component may be exerted on the work. It will be noted that the opposed faces of the grinding wheel and regulating wheel are spaced from one another to 40 provide a grinding throat therebetween. It will further be noted that the axis of the grinding wheel and its spindle is disposed at an angle to the axis of the work 20 so that a plane face on the grinding wheel may form an angularly related face on the work 20 as compared to the stem or body portion 21.

The work 20 is supported in the grinding throat by peripheral engagement of its stem 21 with the active face of a work rest blade 22 adjustably supported in a slot or way formed in block 23 carried by the inner end of the lower slide 15. Pressure rolls 24 are provided for holding the stem 21 of the work against the active face of the regulating wheel so as to insure proper ro-

tation of the said work about the axis of said stem which was previously ground and about the axis of which the valve seat must be generated. The work rest block 23 is provided on its inner end with a supporting lug 25 from which an end stop 26 extends for properly positioning the work relative to the faces of the grinding and regulating wheels.

In order to initially set up the machine and to provide the proper grinding throat the regulating wheel unit is adapted to be actuated relative to the bed along the ways 14 toward and from the grinding wheel. For this purpose there is provided and adjusting screw 27 having its threaded end in engagement with a nut 28 oscillatably journaled in the upper slide 17 and the outer end of the screw 27 is supported in a bearing 29 carried by the base or bed 10. A hand or pilot wheel 30 is mounted on the exterior end of the screw 27 whereby the said screw 27 may be actuated. When adjusting the screw 27 by the hand or pilot wheel 30 the nut 28 is held against oscillation by a hand lever 31. This hand lever 31 is employed for effecting the normal feed of the work and grinding wheel by oscillating said nut 28 to cause the same to travel along the screw and carry with it the slides, regulating wheel and work. The parts are so positioned that a movement of the handle from the vertical position, shown in Figure 2, through ninety degrees in a counterclockwise direction to a horizontal position effects a feed of the work and grinding wheel corresponding to the stock removal. Return of the handle to the position shown in Figure 3 opens the grinding throat to permit a replacement of the finished work piece on the work rest blade 22.

The parts bear substantially the relation to one another illustrated in Figure 2 with the inner portion of the grinding wheel face engaging the entire surface or valve seat of the work to be ground, and as the handle 31 is actuated, the grinding wheel and its spindle, near the end of the movement of the handle 31, is reciprocated across the face of the work. This is accomplished by providing a dog 32 on the inner surface of the lever 31 for tripping an hydraulic valve 33 which has connected therewith inlet line 34 and outlet 35. The former extends to a suitable source of hydraulic pressure, air, oil or the like, while the latter extends to the spindle reciprocating mechanism indicated as an entirety by numeral 36 which is secured to the end of the pedestal 11 and having suitable connection with the spindle 12. As shown in Figure 4 the spindle reciprocating mechanism 36 comprises a casing or housing consisting of three sections, 37, 38 and 39, being secured to one another by bolts 40 and 41. Bolts 40, in addition to clamping the parts together, secure the reciprocator as a unit to the end of the pedestal 11. The central section of the housing 38 is provided with a comparatively large bore 42 forming the cylinder for piston 43 while the end sections 37 and 39 constitute the heads for the said cylinder and, in addition, are provided with bores 44 forming bearings for the reduced extended portions 45 of the piston. The piston 43 is centrally bored to receive the reduced terminal portion 46 of the spindle 12 and forms a journal therein terminating in an enlarged counterbore formed in the rearmost piston extension 45. An anti-friction thrust bearing 47 is enclosed within said counterbore and forms a connection with the spindle extension 46.

76 Reference is now made to the diagrammatic

view, Figure 7, showing the complete hydraulic circuit for actuating the piston in its cylinder. A pump 48 is provided having a suction line 49 extending therefrom and terminating in a suitable tank or reservoir 50. Pressure line 51 extends from the pump 48 and has branching therefrom branch pressure lines 52 and 52a, the former being employed for operating the spindle reciprocator and the latter for supplying lubricant to the spindle bearings. For this purpose branch line 52a includes a pressure reducing valve 53 so that the lubricant for the bearings is not under excess pressure when it enters lubricating lines 54 which terminate at the bearings within the pedestal 11 for properly lubricating the spindle bearings. Branch pressure line 52 has tapped into it the line 34 extending from valve 33. A needle valve 55 regulates the pressure from lines 34 and 52 to the conduit 56 which has branches 57 and 58 terminating at reversing valve 59. Reversing valve 59 in one position connects branch line 57 with a conduit 60 going to one end of the cylinder 42 while in the other position it connects branch 58 with a conduit 61 going to the other end of the cylinder 42. In addition, there is provided a conduit 62 extending from the conduit 60 to one end of the shuttle pilot valve 63 while the other end of said valve is connected by conduit 64 with the cylinder conduit 61. An exhaust conduit 65 connects the chambers of the pilot valve 63 and reversing valve 59 through conduit 66 with the discharge conduit 67 for carrying the spent medium to the tank or sump 50. There is also provided a conduit 76 extending from the needle valve 55 to a check valve 75 which connects the conduit 76 with a second conduit 77. Branch conduits or ports 78 and 79 connect the conduit 77 with the pilot valve chamber. Conduit 80 connects the branch 78 through the pilot valve 63 with one end of reversing valve 59 while conduit 81 connects the branch 79 of conduit 77, through the pilot valve 63, with the other end of reversing valve 59. The outlet conduit 35 of the valve 33 is tapped into the conduit 77 for delivering the pressure of the line 34 to the branch conduits 78 and 79. A shut-off valve 82 is included in the line 35 for preventing a flow of hydraulic pressure for a purpose to appear later. In order to render the reciprocating attachment inoperative conduit or port 81 is connected by a conduit or port 90 with the common discharge conduit 67 and the said port 90 has included therein a stop valve 91 of the needle valve type.

The valve 33 consists of a suitable casing 68 interiorly of which is a spring pressed valve member 69 normally preventing flow of fluid therethrough. A bearing 70 extends from the casing 68 and has slidably mounted therein a plunger 71, the inner end of which contacts with the valve 69 and the outer end engaging an actuating pawl 72 pivotally mounted at 73 to a bracket 74 supporting the valve and its casing.

All of the valves except valve 33 and all of the conduits and ports except lines 34 and 35 and the line extending from the needle valve 55 back to the pump and tank are carried by the several sections 37, 38 and 39 of the reciprocator, as seen by the sectional views Figures 4, 5 and 6. The shuttle pilot valve 63 and the pressure responsive reversing valve 59 and their containing chambers are carried by the central section 38 while certain of the connecting conduits or ports and needle valves are carried by the end sections 37 and 39. A load and fire mechanism is provided for throwing the reversing valve beyond the center posi-

tion for which purpose the said valve 59 is provided with a pair of notches 92 and 93 having tapered sides terminating in the central rib 94. Cooperating with said rib is a spring loaded pawl 95 carried by the central section 38 and having a wedge shaped nose 96. As the valve is shifted from one side to the other the pawl or detent 95 is actuated outwardly to thereby load the spring and as soon as the nose 96 passes over the apex 10 of the rib 94 the spring expands and through the cooperation of the tapered sides of the nose and the tapered walls of the grooves fires the valve 59 past the central position to its other extreme position.

15 The operation of the mechanism is as follows. An hydraulic medium, preferably oil, is taken from the sump or tank 50 through the suction line 49 by the pump 48 and discharged under pressure into conduits 51, 52 and 34. The pressure in line 34 is blocked by the valve 69 while the pressure in line 52 passes through the needle valve 55 to the conduit 56 which, as shown in Figure 7, passes through branch conduit 57 to and through conduit 60 to the inner end of the cylinder 42 for holding the spindle and grinding wheel 13 outwardly, as seen in Figure 2. Excess pressure developed by the pump 48 is discharged through relief valve 83 and conduit 84 to the sump or tank 50. A work piece is placed 20 on the work rest blade 22 with the in-feed lever 31 in the position shown in Figure 3 whereupon the said lever is actuated in a counterclockwise direction, as seen in said Figure 3. This movement of the lever 31 feeds the work into the 25 grinding wheel to effect the proper stock removal therefrom. Near the end of the feeding stroke and when the work piece is substantially to size the dog 32 on the lever 31 engages and actuates the pawl 72 for depressing the plunger 71 and opening valve 69. At this time the stop valve 82 is opened while the check valve 75 is closed to prevent any flow of hydraulic fluid therethrough. The hydraulic fluid being connected through the 30 valve 33 to the conduit 35, the pressure passes 35 through the branch conduit 79, pilot valve 63, conduit 81 to the right hand end of the reversing valve 59, as seen in Figure 7, and shifts the said valve to the left. This movement of the reversing valve to the left connects branch pressure conduit 58 with the conduit 61 which goes to the outer end of the cylinder 42 for shifting the piston contained in said cylinder inwardly, as seen in Figure 2, and correspondingly shifting the spindle and grinding wheel. As soon as the piston reaches the end of its stroke in a forward 40 direction the pressure backs up through the conduit 61 flowing through the conduit 64 for shifting the pilot valve therein and connects the line 35 through branch conduit 78 with the conduit 80. However, as soon as the valve 69 was 45 opened the dog passed beyond the pawl 72 permitting the spring 85 associated with the valve 69 to close same so that at this time no pressure is 50 in the line 35.

55 The lever 31 has now reached the end of its stroke and a short delay is allowed to permit the sparking out of the grinding wheel and work at which time the handle 31 is actuated in a reverse or clockwise direction. It will be noted that the pawl 72 is provided with angularly related cam faces so that upon the reverse movement of the handle 31 dog 32 will actuate and depress same thereby again connecting the pressure line 34 60 with the outlet line 35 so that the pressure imme-

diately flows through branch conduit 78, pilot valve 63 and conduit 80, for again shifting the reversing valve 59 to the position shown in Figure 7 thereby again connecting the parts as there shown for returning the piston to the outward limit of its stroke and consequently so positioning the grinding wheel and its spindle.

65 From the foregoing it will be noted that the spindle and grinding wheel may be either continuously or intermittently reciprocated and that they may be shifted at any point in the cycle of operation of the device depending on the effective position of dog 32. By this construction the major portion of the grinding operation is performed by a part only of the grinding wheel to 15 substantially reduce the work to size at which time the remainder or relatively true portion of the face of the grinding wheel is operatively associated with the work to reduce same to the desired size and produce the proper finish thereon. It is sometimes desirable to have a continuous reciprocation of the grinding wheel and its spindle which would only mean the shutting off of the stop valve 82 and the releasing of relief valve 75 so that the pressure in line 34 is blocked 20 at 82 and has no effect on valve 59 irrespective of the opening or closing of valve 69. The relief valve at 75 is of the character shown at 47 in Ernst Patent 1,938,758 and as described in that patent normally provides a greater resistance to 25 fluid flow into line 77 than that required to effect a reciprocating movement of the spindle. However, when the spindle reciprocating piston has moved to its limit of movement, the continued action of the pump will build up a sufficient 30 pressure in line 76 to open the relief valve at 75 when the actuating fluid as directed by valve 63 will suitably exert its force against one or the other end of valve 59 to reverse the connections 35 of the pressure fluid to the hydraulic reciprocator and thus reverse its direction of movement. It will thus be understood that by loosening the control handle 92^a, valve 75 will be permitted to 40 function under this pressure reactance for effecting automatic continuous reciprocation of the 45 spindle. On the other hand by tightening this valve so that it will not respond to pressure conditions and loosening valve 82, the system is conditioned for intermittent single reciprocating 50 strokes dependent on actuation of plunger 71 as 55 by shifting of lever 31 and its associate dog 32.

To render the oscillating attachment inoperative the stop valve 91 is opened so that no back pressure is built up in conduit or line 81 thereby preventing a shifting of the reverse valve 59 55 which at this time is held against movement by the spring loaded pawl or detent.

What is claimed is:

1. In a grinding machine the combination with a bed, of a rotatable spindle supported thereby, a grinding wheel on one end of said spindle, means supporting a work piece adjacent the grinding wheel, means for effecting a relative feed between the work and grinding wheel, and an hydraulic spindle oscillator normally holding the spindle and grinding wheel against axial reciprocation but energizable by the work feeding means.

2. In a spindle reciprocating mechanism the combination of a spindle, means rotatably supporting said spindle, and means for axially reciprocating the spindle in its support comprising a pressure line, a pair of branch pressure lines extending therefrom, a pressure responsive valve in said branch pressure lines, and means render-

- ing one of said branch pressure lines inoperative whereby either a continuous reciprocation or an intermittent reciprocation of the spindle is obtained.
5. In a spindle reciprocating mechanism the combination of a spindle, a support for the spindle, and means for hydraulically reciprocating said spindle including a piston secured to the spindle, a cylinder for the piston, conduits extending from opposite ends of the cylinder, a pressure responsive reversing valve at the end of the cylinder conduits, a pressure line terminating at the reversing valve, branch pressure lines extending from the main pressure line for effecting the reciprocation of the valve, pressure responsive means in one of said branch transmission lines for automatically reversing the valve for effecting a continuous reciprocation of the spindle, and normally inoperative means in the other branch pressure line for effecting intermittent reciprocation of the spindle.
4. In a spindle reciprocating mechanism the combination of a spindle, a support for the spindle, and means for hydraulically reciprocating said spindle including a piston secured to the spindle, a cylinder for the piston, conduits extending from opposite ends of the cylinder, a pressure responsive reversing valve at the end of the cylinder conduits, a pressure line terminating at the reversing valve, branch pressure lines extending from the main pressure line for effecting the reciprocation of the valve, pressure responsive means in one of said branch transmission lines for automatically reversing the valve for effecting a continuous reciprocation of the spindle, normally inoperative means in the other branch pressure line for effecting intermittent reciprocation of the spindle, and means for rendering either of the last mentioned means inoperative.
5. In a spindle reciprocating mechanism the combination with a spindle, a support therefor, of an hydraulic reciprocator comprising a piston secured to the spindle, a cylinder for the piston, conduits extending from opposite ends of the cylinder, an hydraulic pressure source, a pressure actuatable reversing valve connecting the pressure source with either of the cylinder conduits, a pair of conduits extending from the pressure source to the reversing valve for actuating same thereby, pressure responsive means in one of said conduits for reversing the reversing valve at each end of the piston stroke to effect a continuous reciprocation of the spindle, and a manually actuatable valve in the other conduit for manually effecting a reversing of the reversing valve to intermittently reciprocate the spindle.
6. In a spindle reciprocating mechanism the combination with a spindle, a support therefor, of an hydraulic reciprocator comprising a piston secured to the spindle, a cylinder for the piston, conduits extending from opposite ends of the cylinder, an hydraulic pressure source, a pressure actuatable reversing valve connecting the pressure source with either of the cylinder conduits, a pair of conduits extending from the pressure source to the reversing valve for actuating same thereby, pressure responsive means in one of said conduits for reversing the reversing valve at each end of the piston stroke to effect a continuous reciprocation of the spindle, a manually actuatable valve in the other conduit for manually effecting a reversing of the reversing valve to intermittently reciprocate the spindle, and additional means for rendering either of the pressure conduits inoperative.
7. In a grinding machine the combination of a grinding wheel having an operative face wider than the width of work to be operated upon thereby, means for feeding the work and part of the face of the grinding wheel relative to one another, and means for subsequently feeding the grinding wheel relative to the work to associate the remaining portion of the face of the grinding wheel and work.
8. In a centerless grinder the combination of a pair of opposed grinding and regulating wheels forming a grinding throat therebetween, the grinding wheel having an operative face wider than the portion of the work to be ground, a work rest blade within the grinding throat for supporting the work, and means for operatively associating the work with a part of said grinding wheel face and associating the balance of said grinding wheel face and work for finish grinding said work.
9. In a centerless grinder the combination of a pair of opposed grinding and regulating wheels forming a grinding throat therebetween, the grinding wheel having an operative face wider than the portion of the work to be ground, a work rest blade within the grinding throat for supporting the work, means for effecting a relative feed between the work and a portion of the grinding wheel face, and means subsequently feeding the grinding wheel relative to the work to associate the remaining portion of the face of the grinding wheel and work.
10. In a centerless grinder the combination of a pair of opposed grinding and regulating wheels forming a grinding throat therebetween, a work rest blade in said throat for holding a work piece in engagement with the regulating wheel, means for feeding said regulating wheel, work rest blade and work supported thereby as a unit toward the grinding wheel, and means operable by said feeding means for effecting an axial reciprocation of the grinding wheel relative to the work.
11. In a centerless grinder the combination of a pair of opposed grinding and regulating wheels forming a grinding throat therebetween, a work rest blade in said throat for holding a work piece in engagement with the regulating wheel, means including a manually oscillatable handle for feeding said regulating wheel, work rest blade and work supported thereby as a unit toward the grinding wheel and means operable by said handle when oscillated in a given direction for axially reciprocating the grinding wheel in one direction and for reciprocating the grinding wheel in the reverse direction when reversely oscillating the hand lever.
12. In a grinding machine of the class described the combination of a bed, bearings supported by the bed, a spindle rotatably journaled in the bearings, a grinding wheel secured to the spindle for rotation therewith, means adjacent the grinding wheel for supporting a work piece while being operated upon by the grinding wheel, a feeding mechanism for effecting a relative feed between the work and the grinding wheel for reducing said work to its final size and form, and means operable substantially at the conclusion of the feeding operation when the work is substantially to final form for axially reciprocating the grinding wheel and its spindle relative to the supporting bearings across the work.
13. In a grinding machine of the class described

the combination of a bed, bearings supported by the bed, a spindle rotatably journaled in the bearings, a grinding wheel secured to the spindle for rotation therewith, means adjacent the grinding wheel for supporting a work piece while being operated upon by the grinding wheel, a feeding mechanism for effecting a relative feed between the work and the grinding wheel for reducing said work to its final size and form, and means operable substantially at the conclusion of the feeding

operation when the work is substantially to final form for axially reciprocating the grinding wheel and its spindle relative to the supporting bearings across the work, said spindle and grinding wheel shifting mechanism including a reciprocating mechanism operable upon the spindle and the feeding mechanism being controlled by a manually operable lever which energizes the reciprocating mechanism. 5

EUGENE F. HAAS. 10
